(57) **CLAIM**

The ornamental design for a bartop gaming device as shown and described.

DESCRIPTION

FIG. 1 is a front isometric view of a bartop gaming device in accordance with a first embodiment of the present invention;

FIG. 2 is a top plan view of the bartop gaming device illustrated in FIG. 1;

FIG. 3 is a front elevation view of the bartop gaming device illustrated in FIG. 1;

FIG. 4 is a first side elevation view of the bartop gaming device illustrated in FIG. 1;

FIG. 5 is a second side elevation view of the bartop gaming device illustrated in FIG. 1;

FIG. 6 is a rear elevation view of the bartop gaming device illustrated in FIG. 1;

FIG. 7 is a bottom plan view of the bartop gaming device illustrated in FIG. 1;

FIG. 8 is a front isometric view of a bartop gaming device in accordance with a second embodiment of the present invention;

FIG. 9 is a top plan view of the bartop gaming device illustrated in FIG. 8;

FIG. 10 is a front elevation view of the bartop gaming device illustrated in FIG. 8;

FIG. 11 is a first side elevation view of the bartop gaming device illustrated in FIG. 8;

FIG. 12 is a second side elevation view of the bartop gaming device illustrated in FIG. 8;

FIG. 13 is a rear elevation view of the bartop gaming device illustrated in FIG. 8; and,

FIG. 14 is a bottom plan view of the bartop gaming device illustrated in FIG. 8.

The broken lines in the drawings are for the purpose of illustrating portions of the bartop gaming device which form no part of the claimed design.

1 Claim, 8 Drawing Sheets
